UNITED STATES PATENT OFFICE.

LAWRENCE A. SUBERS, OF CLEVELAND, OHIO.

FABRIC HAVING LAYERS OF VARIABLE EXTENSIBILITY.

1,021,014.

Specification of Letters Patent. Patented Mar. 26, 1912.

Application filed June 23, 1911. Serial No. 634,983.

To all whom it may concern:

Be it known that I, LAWRENCE A. SUBERS, a citizen of the United States, and resident of Cleveland, in the county of Cuyahoga and State of Ohio, have invented certain new and useful Improvements in a Fabric Having Layers of Variable Extensibility, of which I hereby declare the following to be a full, clear, and exact description, such as will enable others skilled in the art to which it appertains to make and use the same.

The objects of the invention are to provide a tubular fabric composed of bands of parallel equally spaced and interwound fibrous elements, and adapted to the various uses of high pressure tubing such as tubing used for hydraulic or pneumatic pressure including fire and air brake hose, pneumatic tires, belting, etc., the fabric being so constructed as to overcome to a predetermined degree the tendency to elongate or expand in a lateral direction, and composed of separate layers in which the degree of extensibility can be controlled, to secure a predetermined expansion and contraction thereof, and avoid the movement or "working" of one layer upon another, and the consequent destruction of the fabric. The machine for constructing this fabric is described in my co-pending application bearing Serial No. 634,982 filed June 23, 1911. In a previous application Serial No. 587,632, I have described one method of construction by means of which this result can be accomplished, that is, by varying the number of twists per inch in the cords composing the layers, the cords composing the inner layers having the greater number of twists per inch and the outer ones a less number, thus giving the inner layers a greater capability for stretching than the outer layers. The effect is that the inner layers are first affected by the internal pressure and are free to expand and transmit the pressure to the outer layers before reaching the elastic or bursting limit. In addition two classes of fabric layers are employed, a layer or layers of angularly laid bands adapted to resist the longitudinal pressure, and a layer or layers of circumferentially or spirally laid bands adapted to resist diametrical pressure. The relation of one class of layers to the other class serving to obtain the required balance of strength in the hose and control the amount of total elongation, contraction, and expansion to a predetermined degree.

The flattened band from which the present fabric is composed is similar to the band shown and described in my former application for Letters Patent bearing Serial No. 600,313, and the control of the capability for stretching of the band is not obtained by variations in the number of twists in cords composing the band but in the angle at which the component flexible fibrous elements of the band are wound therein. This angle of winding can be varied at pleasure and since the ration of elongation possible is less when the angle of winding is less than about 15° to the edge of the band, it is of great importance to wind at this small angle. This angle can be varied at pleasure by constructing the band in a machine invented by me and described in an accompanying application, and can be wound at a smaller angle or at a much wider angle if desired. The inner layer is formed of interwound parallel bands composed of elements laid at a wide angle to permit of the greatest expansion of the inner layer and the angle of winding of the fibrous elements composing the outer layers will be at a narrow angle according to their distance from the inner layer so as to permit of less expansion thereof. The control of relative extensibility of the several layers is also obtained by varying the angle of winding the bands in the said layers.

The intermediate layer is designed to control the extensibility of the tube in a diametrical direction and the inner and outer layers control the longitudinal extensibility of the tube.

The invention comprises the bands constructed as described and the fabric tube constructed therefrom and having several layers, each layer having a predetermined ratio of extensibility to the other layers.

The invention is illustrated in the accompanying drawings, where—

Figure 1 is a side elevation of a tapered mandrel upon the large diameter of which the band elements are first wound under a predetermined tension and the completed band is pulled over the tapered portion, thus bringing the separated flexible elements closely together, making the angle smaller at which they lie; Fig. 2 is a plan view of the band; Fig. 3 is a transverse section; Fig. 4 is a side elevation of a hose showing three layers partially removed to disclose the structure; Fig. 5 is a longitudinal section

showing the same construction in a tire casting; Fig. 6 is a transverse section of the casting shown in Fig. 5.

In these views A, A are flattened bands 5 formed preferably of groups of parallel yarns or threads of a predetermined diameter cohering together, the width of the groups of parallel yarns or threads forming the bands being also predetermined by the 10 number of yarns or threads lying parallel to each other, while the number of parallel groups of parallel yarns or threads is such that they approximately cover the surface of the mandrel at its smaller end lying at 15 a predetermined angle, while at the same time being coated on the exterior surface and also thoroughly saturated throughout the interior with elastic binding material such as vulcanizable rubber or other adhesive substance. These bands are formed 20 of interwound groups of yarns upon a mandrel B in tubular form as described in my previous application for Letters Patent Ser. No. 600,313, but are first wound as shown in 25 Fig. 1 so as not to cover the entire surface of the mandrel, but at a predetermined equal distance apart.

The mandrel has a tapered extremity C terminating in a cylindrical portion D of 30 smaller diameter than the portion A. As the tubular band is drawn off from the mandrel it first passes over the tapered portion C and then over the reduced portion D and therefore the pull upon the band will elongate it and the groups of yarns or threads 35 or strands will assume a much smaller angle to the axis of the mandrel and lie closely together, covering completely the surface of the reduced portion D of the mandrel. One 40 of the reasons for not immediately winding the yarns at this small angle is that a mandrel of the small diameter required to form the finished band might not be strong enough to sustain the tension of the yarns 45 without undue bending or deflection.

By varying the size of the mandrel at the small end of the taper the width of the band can be controlled and by varying the relative spreads of the pulling and winding 50 means employed the angle of winding can be varied indefinitely. The separate layers can then be wound of selected bands of predetermined extensibility to obtain the degree of extensibility desired in the individual 55 bands. The bands in the inner layer L are preferably wound upon a rubber lining E' at an angle of 45° in opposite directions. The intermediate layer F is wound spirally and the other layer G is similar to the first 60 layer in the arrangement of bands, as shown in Figs. 4 and 5, the angle at which the bands are wound being smaller than in the inner layers, approximately. The angle at 65 which the fibrous elements are wound in the bands of which the several layers are com-

posed varies in the figures in an obvious manner.

The groups L of yarns in the inner layer are laid at an angle wider than the groups L' in the central layer F, and those in the 70 central layer are wound at a wider angle than those L² in the outer layer. An outer coating or cover H completes the fabric on the exterior surface.

The layers may comprise bands in which 75 the angle at which the flexible members are wound is varied in each layer, or the bands may be wound at different angles in each layer, or a combination of both forms of structure may be employed.

Having described the invention what I 80 claim as new and desire to secure by Letters Patent is:

1. The combination in a tubular fabric composed of layers of fabric, each layer 85 comprising a laminated-cohesive-interwound formation of parallel fibrous bands crossing each other at an angle, the angle at which the bands cross each other in the inner layer being wider relatively to the edge and axis 90 of the fabric than the angle of winding of the bands comprising the outer layers.

2. The combination in a tubular fabric composed of separate superimposed fabric 95 layers, each layer formed of laminated-cohesive-interwound parallel members crossing each other at an angle, the angle at which the said members cross each other in each layer being predetermined, and lessening in width from the inner to the outer layer, the variation in the respective angles 100 governing the relative ratios of expansibility of the several layers.

3. In a tubular fabric, an inner lining, an outer covering, an inner layer composed of bands the fibrous elements of which cross each other at a predetermined angle and consist of parallel lying yarns of predetermined diameter and number, and said bands cross each other at a predetermined angle, an intermediate layer composed of spirally laid bands, the fibrous elements of which cross each other at a less angle than in the bands of said first layer, and an outer layer composed of bands, the fibrous elements of which cross each other at a smaller angle than in the bands of either of the previously mentioned layers.

4. In a fabric, a layer constructed of laminated interwound parallel cohesive members, and layers superimposed thereon of laminated interwound parallel cohesive members, the angles at which the members of the inner layer are wound being wider than the angle of winding the next succeeding layer, and the angle of winding each succeeding layer being a predetermined less angle.

5. A fabric tube composed of layers of interwound laminated cohesive bands, each 130

band in each layer composed of laminated interwound cohesive members, the members of the bands in the inner layer being wound at a wider angle than in the succeeding 5 layers.

6. In a tubular fabric, outer and inner fabric layers therein, each layer composed of bands crossing each other at an angle and an intermediate layer composed of spirally 10 wound bands, each band composed of flexi-

ble crossing members cohering together, the members in the inner layer crossing each other at a wider angle than the members in the outer layers.

In testimony whereof, I hereunto set my 15 hand this seventh day of June 1911.

LAWRENCE A. SUBERS.
